**"N" OUTPUT TRANSMISSION LINE AND
TRANSFORMER HYBRID**

George E. Petts III, Annapolis, and Robert E. Evans, Baltimore, Md., assignors, by mesne assignments, to the United States of America as represented by the Secretary of the Navy

Filed Oct. 20, 1961, Ser. No. 146,665
6 Claims. (Cl. 333—11)

This invention relates to line hybrids of the type which provide a number of outputs derived from one input wherein these outputs are isolated from one another without any theoretical loss of power. More particularly, the invention relates to an "N" type (any number of outputs) of the transmission and transformer hybrid.

Devices of the form where a single input is to be fed into a number of systems or equipments require the use of a circuit for dividing up this available input without any interaction between the respective outputs. A simple example of one such system requiring input distribution is an antenna system where in one case it is desired to connect the antenna to a number of receivers and in another to apply the signal from a transmitter to a multiple antenna array. In the past, it has been necessary in order to provide more than two balanced isolated outputs to employ a cascaded hybrid arrangement. This in effect requires the use of hybrids each of which have two outputs. These hybrids are connected in such a fashion that for each output another cascaded hybrid is placed thereacross. In other words, the two outputs of the first hybrid are terminated by the inputs of two other hybrids and these in turn are terminated by the next succeeding four hybrid stage which has eight outputs. The progression is continued until the desired number of outputs are attained. Basically, it is obvious that by this cascaded method the number of outputs obtainable with equal signal or input power division is an integral power of two (2^n). If someone therefore is in need of an odd number of outputs or a number that is not a multiple of 2^n he must discard a certain number of outputs. Economically, this cascaded method is both unsound and unrealistic when one considers that not only must certain outputs be discarded but they must also be properly terminated in order to insure impedance matching and equal power distribution. Further, the number of unused outputs will increase with any large number of required outputs and the bulk, weight and overall size of the equipment will increase substantially while the available power at any one output will decrease.

It might be assumed that this problem can be solved by merely providing the required number of outputs but this is not a simple problem when one considers the other necessary features such as equal power distribution, impedance matching and most important the high degree of electrical isolation between the outputs. Presently available hybrids do satisfy these requirements but due to their principle of operation they can only provide a single pair of outputs for each input and therefore they must be cascaded as previously described when outputs in excess of two are desired.

An object of this invention is to provide a device having a signal input and any number of desired outputs which are balanced and isolated from one another.

Another object is to provide a simple, practical, efficient inexpensive and dependable "N" output hybrid.

Still another object is to provide an "N" hybrid transmission and transformer system of balanced and isolated outputs.

Other objects and advantages will be apparent from the following description of embodiments of the invention, and the novel features thereof will be particularly

2

pointed out hereinafter in connection with the appended claims.

FIG. 1a is a diagram of a typical transmission line distribution system.

FIG. 1b is a diagram of the transmission system of FIG. 1a using the legend notation.

FIG. 2 is a diagram of a transmission line distribution system embodying the principle of this invention.

FIG. 3 is another embodiment of the invention.

FIGS. 4 and 5 illustrate schematically a transformer hybrid made in accordance with this invention.

The circuit of FIG. 1a illustrates a typical network for the distribution of a signal to various outputs. For the sake of clarity only three branches have been shown although any number N may be used. The circuit consists of N quarterwave transmission lines 10 connected in parallel at one end to a common junction or terminal 11 across which a source 12 may be placed. Each transmission line 10 at its end opposite the source or terminal 11 is terminated in a load impedance Z_L . In order to properly match the source 12 to its input circuit which includes the transmission line 10 whose characteristic impedance is Z_0 and the load Z_L the proper line impedance is necessary. The impedance for each quarter-wave branch is

$$Z_b = \frac{Z_0^2}{Z_L}$$

and if there are N branches in parallel then the total impedance is equal to

$$\frac{Z_0^2}{Z_L N}$$

In order to properly match the source impedance Z_s it should effectively be equal to the total branch impedance namely

$$Z_s = \frac{Z_0^2}{N Z_L} \text{ or } Z_0 = \sqrt{N Z_L \cdot Z_s}$$

If the source impedance is equal to the load impedance this reduces to

$$Z_0 = \sqrt{N Z_L}$$

FIG. 1b and the accompanying legend show the circuit of FIG. 1a using the notations of the legend. Considering now the circuit of FIG. 1 it is quite obvious that the outputs are not isolated from each other as there are direct paths through the terminal 11 connecting these outputs together. It is to solve this problem that the two or dual isolated output hybrid was devised. On the other hand this solution did not alleviate the difficulties that arise when the number of required outputs is greater than two and not a multiple of 2^n . FIG. 2 illustrates an embodiment made in accordance with this invention as applied to a triple output and for clarity the notation of the legend of FIG. 1 has been employed. The source 22 is again connected to the output 23 by transmission line 20 which in effect is the equivalent circuit of FIG. 1. A direct path is now provided between each of the outputs, which path, comprises in each case a length of transmission line 24, a balance termination 25, a phase inverter 26 (180° phase shift) and a second transmission line 27. The transmission lines are chosen so that their characteristic impedance maintains a matched condition between the outputs and the interposed components. The balance termination may be of the resistive type or a tuned network while the phase inverter made by any suitable device as for example, a simple RC phase shift network or a coupled winding. With this arrangement, an injected signal will divide equally between the paths (from one output to the source, then to a second output, and through the inverting path between the outputs, and with equal impedances the two signals arriving at an output will be

180° out of phase due to the inverting path thus providing electrical isolation (cancellation) between each of the outputs.

In all cases irrespective of the number of outputs (N) a second inverted path must be introduced between every pair of outputs where isolation is desired. FIG. 3 illustrates this for a line hybrid having four separate isolated outputs and similar systems can be devised with any number of isolated outputs employing the principle of this invention. The following relationships are useful in deriving these networks wherein N is the number of outputs.

(a) The characteristic impedance of the transmission line is $Z_0 = \sqrt{N}Z_L$ when the source and load impedances are equal,

(b) The number of individual transmission line segments is $(5N-6)$,

(c) The number of resistors in which no power is dissipated is $(2N-3)$,

(d) The total number of terminations and sources is $(3N-2)$, and

(e) The number of transmission lines attached to the input or to any output is N.

In the illustrated embodiment of FIG. 4 a number of identical transformers 40 each also designated as T_1, T_2, T_3 and T_N form a part of an "N" output transformer hybrid. Although only three such transformers have been shown any number may be used depending on the number of outputs required. That is, the number of outputs (N) is equal to the number of transformers (N). Each transformer 40 is provided with one secondary winding 41 and N primary windings of which one 42 is an input winding and the others 43 are balance windings. The turns ratio of the primary to the secondary winding is

$$\frac{1}{\sqrt{N}}$$

and the dot associated with each winding indicates in effect the direction of the winding. The input windings 42 are connected in series with the dot end of one winding connected to the undotted end of the next succeeding winding. Across these series windings is the signal input which for later explanation is represented by a source resistance 44. A current i_s is represented as flowing in this input path. One balance winding 43 of each primary of each transformer is connected to a balance winding of another separate transformer so that every transformer is connected to another by a balance winding. The balance windings are reverse connected such that the dotted ends are joined and undotted ends also joined. A balancing element, as for example resistor 45, is interposed between the balance windings and the current flowing in this balance loop is designated as $i_1, i_2, \dots, i_N$. In FIG. 4, the balancing elements or resistors 45 are connected between the "start" ends of the balance windings while the "finish" ends are directly connected.

The transformer hybrid must satisfy three conditions, namely, provide isolation between the outputs, apply equal power to each output and match the source to the output. A circuit analysis of FIG. 4 will clearly show that the first condition is fully satisfied while a similar analysis of FIG. 5 will show the satisfaction of the two remaining conditions. Since there may be as many identical transformers 40 as desired we need consider only one of these, such as, T_j . The current i_j flowing in the secondary may be expressed in terms of the primary currents as,

$$i_j = \frac{i_s}{\sqrt{N}} + \frac{i_1 + i_2 + \dots + i_{j-1}}{\sqrt{N}} + \frac{i_{j+1} + \dots + i_N}{\sqrt{N}} \quad (1)$$

which reduces to

$$= \frac{1}{\sqrt{N}} \left[i_s + \sum_{a=1}^{a=j-1} i_a + \sum_{a=j+1}^N i_a \right] \quad (1a)$$

where i_a is the balance current in any transformer. The current i_s in the input winding 42 in terms of the output voltages E and the source impedance is

$$i_s = \left[\frac{E_1}{\sqrt{N}} + \frac{E_2}{\sqrt{N}} + \dots + \frac{E_N}{\sqrt{N}} \right] \frac{1}{r_s} \quad (2)$$

where r_s is the source impedance.

$$i_s = \frac{1}{\sqrt{N}} r_s \sum_1^N E_a \quad (2a)$$

The balance winding current i_a flowing between transformer T_j and any other transformer can be expressed in terms of the output voltages and the balance resistance r_b as:

$$i_a = \left[\frac{E_j}{\sqrt{N}} - \frac{E_a}{\sqrt{N}} \right] \frac{1}{r_b} \quad (3)$$

$$i_a = \frac{1}{\sqrt{N} r_b} [E_j - E_a] \quad (3a)$$

Now combining Equations 1a, 1b and 1c we have:

$$i_j = \left[\frac{1}{\sqrt{N} r_s} \sum_1^N E_a \right] \frac{1}{\sqrt{N}} + \sum_1^{j-1} \left[\frac{E_j}{\sqrt{N}} - \frac{E_a}{\sqrt{N}} \right] \frac{1}{r_b} + \sum_{j+1}^N \left[\frac{E_j}{\sqrt{N}} - \frac{E_a}{\sqrt{N}} \right] \frac{1}{r_b} \quad (4)$$

since

$$\sum_1^N E_a = \sum_1^{j-1} E_a + E_j + \sum_{j+1}^N E_a$$

$$\sum_1^{j-1} \frac{E_j}{\sqrt{N}} - \frac{E_a}{\sqrt{N}} = \frac{[(j-1)-1]E_j}{\sqrt{N}} - \sum_1^{j-1} \frac{E_a}{\sqrt{N}}$$

$$\sum_{j+1}^N \frac{E_j}{\sqrt{N}} - \frac{E_a}{\sqrt{N}} = \frac{[N-(j+1)]E_j}{\sqrt{N}} - \sum_{j+1}^N \frac{E_a}{\sqrt{N}}$$

and for balance $r_b = r_s$ then

$$i_j = \frac{1}{N r_s} \left[\sum_1^{j-1} E_a + E_j + \sum_{j+1}^N E_a \right] + \frac{[(j-1)-1] E_j}{r_s \sqrt{N}} - \frac{1}{r_s \sqrt{N}} \sum_1^{j-1} \frac{E_a}{\sqrt{N}} \frac{[N-(j+1)] E_j}{\sqrt{N} r_s} - \frac{1}{r_s \sqrt{N}} \sum_{j+1}^N \frac{E_a}{\sqrt{N}} \quad (4a)$$

$$i_j = \frac{E_j}{N r_s} + \frac{E_j}{r_s N} [(j-1)-1] + [N-(j+1)] \quad (4b)$$

which reduces to

$$i_j = \frac{1}{N r_s} [E_j + (N-1)E_j] \quad (4c)$$

$$i_j = \frac{E_j}{r_s} \quad (4d)$$

Equation 4d shows that the output current i_j of any transformer is dependent only on the voltage across the output and the balance or source impedance. Therefore, since the output of any other transformer does not enter into the expression each output is isolated or is effectively independent of every other output.

FIG. 5 illustrates the same embodiment as FIG. 4 except it is restricted to a showing limited to three transformers and that the source 50 is represented as a voltage E_s and an impedance r_s and a load resistance r is across each of the outputs. Analyzing this circuit starting with the input loop path we have:

$$E_s = i_s r_s + \frac{1}{\sqrt{N}} \sum_1^N E_a \quad (5)$$

where E_a is the output voltage of any transformer. Solving for i_s

$$i_s = \frac{1}{r} \left[E_s - \frac{1}{\sqrt{N}} \sum_{a=1}^N E_a \right] \quad (6)$$

Considering now any transformer T_j the current in the balance circuit between T_j and T_a is

$$i_a = \frac{1}{r} \left[\frac{E_j}{\sqrt{N}} - \frac{E_a}{\sqrt{N}} \right] = \frac{1}{r} (E_j - E_a) \quad (7)$$

The primary and secondary currents of T_j are related as follows:

$$\frac{i_s}{\sqrt{N}} = i_j + \frac{1}{\sqrt{N}} \left[\sum_{a=1}^{j-1} i_a + \sum_{a=j+1}^N i_a \right] \quad (8)$$

which becomes

$$i_s = \sqrt{N} i_j + \sum_{a=1}^{j-1} i_a + \sum_{a=j+1}^N i_a \quad (8a)$$

Combining or equating 8a and 6

$$\frac{E_s}{r} - \frac{1}{\sqrt{N}} \sum_{a=1}^N E_a = \sqrt{N} i_j + \sum_{a=1}^{j-1} i_a + \sum_{a=j+1}^N i_a \quad (9)$$

and from 7

$$\sum_{a=1}^{j-1} i_a = \sum_{a=1}^{j-1} \frac{1}{\sqrt{N} r} (E_j - E_a) = \frac{[(j-1)-1]E_j}{\sqrt{N} r} - \sum_{a=1}^{j-1} \frac{E_a}{\sqrt{N} r}$$

similarly

$$\sum_{a=j+1}^N i_a = \frac{[N-(j+1)]E_j}{\sqrt{N} r} - \sum_{a=j+1}^N \frac{E_a}{\sqrt{N} r}$$

and

$$\sum_{a=1}^{j-1} i_a + \sum_{a=j+1}^N i_a = \frac{1}{\sqrt{N} r} \left[(N-1)E_j - \sum_{a=1}^{j-1} E_a - \sum_{a=j+1}^N E_a \right]$$

therefore 9 becomes

$$\frac{E_s}{r} = \frac{1}{\sqrt{N} r} \sum_{a=1}^N E_a + \sqrt{N} i_j + \frac{1}{\sqrt{N} r} \left[(N-1)E_j - \sum_{a=1}^{j-1} E_a - \sum_{a=j+1}^N E_a \right] \quad (10)$$

and with

$$\sum_{a=1}^N E_a = \sum_{a=1}^{j-1} E_a + E_j + \sum_{a=j+1}^N E_a$$

(10) simplifies to

$$\frac{E_s}{r} = \sqrt{N} i_j + \frac{E_j}{r} \left(\frac{(n-1)}{\sqrt{N}} + \frac{1}{\sqrt{N}} \right) = \sqrt{N} i_j + \frac{E_j}{r} \left(\frac{N}{\sqrt{N}} \right) \quad (11)$$

$$E_s = r \sqrt{N} i_j + E_j \sqrt{N} \quad (12)$$

$$i_j r = E_j$$

$$E_s = r \sqrt{N} \frac{E_j}{r} + E_j \sqrt{N} = 2 \sqrt{N} E_j$$

combining

$$E_s = \frac{E_s}{2 \sqrt{N}} \quad (13)$$

Equation 13 above indicates that the output voltage for any output is dependent only on the input source voltage E_s and independent of any other output. The power available at the output across the load resistor r is:

$$P_r = \frac{E_s^2}{r}$$

and from (13)

$$E_s = \frac{E_s}{2 \sqrt{N}}$$

so that

$$P_r = \frac{E_s^2}{4rN} \quad (14)$$

while the maximum power available from the source is

$$P_{ms} = \frac{E_s^2}{4r} \quad (15)$$

therefore

$$\frac{P_r}{P_{ms}} = \frac{\frac{E_s^2}{4rN}}{\frac{E_s^2}{4r}} = \frac{1}{N} \quad (16)$$

and since there are N outputs the total power delivered by the source to all the loads is

$$P_t = NP_r = N \frac{(P_{ms})}{N} = P_{ms} \quad (17)$$

Equation 17 clearly shows that since the total power available at the source is delivered to the output loads then the hybrid transformer properly matches the source to the output. For the specific case of FIGURE 5, N is equal to three.

Summarizing the "N" output transformer hybrid of FIGS. 4 and 5 and the attendant equations it is obvious that the circuit arrangement divides the available energy or power at the source equally to each of the outputs and further that each of the outputs are isolated from every other output. These equations have been derived without regard to the number of outputs or transformers and therefore apply with equal force to an arrangement having any selected or predetermined number of outputs. For every output there is required an additional transformer and an additional balance winding on each transformer which in and of itself makes this circuit simple, practical and inexpensive when compared to the cascaded arrangement presently used.

In addition to the uses of the "N" output hybrid systems previously mentioned they have particular application in conjunction with power dividers, balanced amplitude and phase detectors. Further, the hybrid of this invention can be used as a directional coupler for various equipment, such as, pulse reflectometers, broadband sweepers and pulse repeaters. The hybrid method herein-described has been used as an antenna coupler wherein it allows the number of equal gain outputs to be adjusted to the gain available from the driver amplifier and thereby alleviates the necessity that the gain of the amplifier be adjusted to give 2^n outputs as is necessary when the cascaded method of interconnection is employed. This feature is especially critical where high frequency distributed amplifiers are in the circuit since there is a limitation on the number of vacuum tubes that can be placed on the grid line due to the vacuum tube grid loading effects.

Obviously many modifications and variations of the present invention are possible in the light of the above teachings. It is therefore to be understood that within the scope of the appended claims the invention may be practiced otherwise than as specifically described.

We claim:

1. An "N" output transformer hybrid wherein the input signal may be equally distributed to any number exceeding two of isolated outputs comprising "N" number, three or more, of transformers each having one secondary winding and "N" primary windings one of said primary windings being an input winding and the remaining primary windings being balance windings, said secondary winding being the output winding, an input path including in series therein input terminals and said input windings of said transformers, a number of balance electrical paths each including in series therein one balance winding of one of said transformers and a balance winding of another of said transformers, said balance windings in said balance path being connected in opposition whereby when a signal is applied to said input terminals the output at said output terminals will be balanced and said output terminal will be electrically isolated from one another.

2. The transformer hybrid according to claim 1 where-
in all of said secondary windings have an equal number
of turns.

3. The transformer hybrid according to claim 2 where-
in the turns ratio of said primary to secondary windings
is one over the square root of the number of transformers.

4. The transformer hybrid according to claim 3 further
including in said balance path in series therewith balanc-
ing means.

5. The transformer hybrid according to claim 4 where-
in said balancing means is a resistor element.

6. The transformer hybrid according to claim 5 where-
in the resistance of said element is equal to the impedance

8
of a signal source which may be connected across said
input terminals.
